Primary Examiner—Prabhakar Deshmukh*Assistant Examiner*—Jean E McCormick(74) *Attorney, Agent, or Firm*—Calfee, Halter & Griswold LLP(57) **CLAIM**

The ornamental design for a doorknob, as shown and described.

DESCRIPTION

FIG. 1 is a rear elevational view of a doorknob of the new design;

FIG. 2 is a top plan view of the doorknob of FIG. 1;

FIG. 3 is a front elevational view of the doorknob of FIG. 1;

FIG. 4 is a perspective view of the doorknob of FIG. 1;

FIG. 5 is a rear elevational view of a second embodiment of

a doorknob of the new design;

FIG. 6 is a top plan view of the doorknob of FIG. 5;

FIG. 7 is a front elevational view of the doorknob of FIG. 5; and,

FIG. 8 is a perspective view of the doorknob of FIG. 5.

The portions of the Figures shown in phantom lines are not part of the claimed design but are for illustration purposes only.

1 Claim, 2 Drawing Sheets
